UNITED STATES PATENT OFFICE.

JAMES GALVIN, OF DETROIT, MICHIGAN.

GATE-VALVE.

SPECIFICATION forming part of Letters Patent No. 415,776, dated November 26, 1889.

Application filed November 10, 1888. Serial No. 290,424. (No model.)

To all whom it may concern:

Be it known that I, JAMES GALVIN, a citizen of the United States, residing at Detroit, county of Wayne, State of Michigan, have invented a certain new and useful Improvement 5 in Gate-Valves; and I do declare the following to be a full, clear, and exact description of the invention, such as will enable others skilled in the art to which it pertains to make 10 and use the same, reference being had to the accompanying drawings, which form a part of this specification.

My invention relates to that class of gate-valves wherein swinging wedges riding against 15 inclined ledges on the case are thereby forced laterally between the disks to force the disks to their seats.

Difficulty has heretofore been experienced 20 in the use of this class of valves, from the fact that when the valve is laid on its side the upper wedge will drop down between the disks, and in attempting to seat the latter the wedge will bind and thus prevent the disks from coming to their proper seats.

25 It is the object of my invention to remedy this by forming one of the wedges integral or rigid with the yoke from which the wedges and disks depend. The other wedge is suspended or swung from the yoke.

30 In the drawings, Figure 1 is a sectional view showing parts in elevation. Fig. 2 is a sectional side elevation from a side at right angles to Fig. 1. Fig. 3 is a horizontal sectional view through the disks; and in Fig. 4 35 is shown a vertical and horizontal section of a variation.

In the above drawings, A represents the 40 valve-case, having the inclined ledges *a a'* on the inner surface.

45 B is the valve-stem, provided at its lower end with screw-threads *b*.

C is a yoke provided with screw-threads *c*, said yoke being adapted to travel on the stem *B*.

50 C' is a wedge formed integral or rigid with the yoke *C*, and C² is a correspondingly-shaped wedge suspended from the opposite side of the yoke by means of the hook *c'*, engaging with the ear *c²* on the wedge *C²*.

55 D are disks suspended from the yoke *C* by the projections *c³*, engaging in the ears *d* of

the disks, said disks being provided with inclined surfaces *d'*, against which the inclined faces *c⁴* of the wedges are adapted to bear.

The operation of the valve will be readily understood. The stem *B*, being supported in the case *A*, is rotated, and the yoke *C*, with the disks and wedges, is lowered. The wedges *C'* and *C²* are tapered, and the edges *c⁵* coming in contact with the inclined ledges *a a'* 60 on the case, the wedge *C²* will be gradually forced inward as it is lowered, while the wedge *C'*, presenting its inclined surfaces *c⁴* to the inner surfaces of the disks, will prevent the latter from being forced laterally by the 65 pressure of the wedge *C²* and insure the perfect seating of the disks. It will be seen that by thus forcing the wedge *C²* inwardly the disks will be gradually forced out until seated. The wedge *C'*, being formed integral or rigid 70 with the yoke, will permit of the valve being laid on its side and still be as easily operated as when in a perpendicular position, since the wedge *C'* is not permitted to drop down between the disks, being held in proper position by the yoke. When an inclined projection is used on the case back of the rigid wedge, the latter is so formed on the yoke that it will not come to a bearing on said projection until the disks have been forced to 75 their seats by the movable wedge. This projection therefore acts simply as an abutment for the rigid wedge after the disks have been seated, and tends in no way to crowd the rigid wedge inward. If desired, the back of 80 the rigid wedge *C'* may be made straight, as at *C²*, and the case itself serve to form an abutment against which it may impinge while the swinging wedge is forcing the disks to 85 their seats. This form is shown in the two views of Fig. 4. When this latter construction is used, the rigid wedge may be open at the back, so as to straddle the ledge *a* on the case, as shown by the lower view of Fig. 4 and by the dotted lines in the upper view of 90 Fig. 4. This is done so that should the wedges and disks be removed from the case the positions of the wedges may be reversed, if desired, and the valve yet be operative.

What I claim is—

100 1. In a gate-valve, the combination, with the valve-case having interior ledges *a a'*, of

a yoke threaded upon the valve-stem and carrying the valve-disks, said yoke provided with one rigid or integral wedge depending therefrom, and one swinging wedge suspended therefrom, said latter wedge adapted to be forced laterally between the disks by impinging against the adjacent ledge, and said rigid wedge adapted to impinge against the opposite ledge, as described, and serve as an abutment, substantially as described.

2. A gate-valve consisting of a valve-case and threaded stem, a yoke bearing two valve-disks, said yoke provided with two depend-

ing wedges between the disks, one swinging and the other rigid, an inclined projection on the case adapted to engage the swinging wedge, and a projection on the case adjacent to the back of the rigid wedge, substantially as described.

In testimony whereof I sign this specification in the presence of two witnesses.

JAMES GALVIN.
